RETRACTABLE TOOL HANDLE

Arthur F. Alexander, Cleveland, Ohio

Application February 24, 1950, Serial No. 146,033

2 Claims. (Cl. 145—64)

1

This invention relates to improvements in double ended screw drivers. It has to do with a bar provided at its ends with screw driver blades of different sizes or types and a handle which is movable along the bar and may be secured to it at either end of the latter.

One of the objects of the invention is the provision of a screw driver having two different blades either one of which may be utilized at a moment's notice.

Another object is the provision of a tool of this character which shall have high inherent strength.

Other objects and advantages will appear as I proceed with the description of that embodiment of the invention which, for the purposes of the present application, I have illustrated in the accompanying drawing, in which

Fig. 1 is a plan view of the tool with the handle at one end thereof.

Fig. 2 is an elevational view of the same with the handle at the opposite end of the tool.

Fig. 3 is a plan view of the bar with its ends finished as screw driver blades and with the handle removed.

Fig. 4 is a cross-sectional view on a larger scale, the view being taken substantially on the line 4—4 of Fig. 2 but showing the latch plate in bar releasing position, and

Fig. 5 is a longitudinal sectional view of a fragment of the handle, the view being taken substantially on the line 5—5 of Fig. 4, but showing the bar locked to the handle.

The tool of this invention comprises two main parts, a solid bar 10 and a handle 11 which may be mounted in either of two operative positions on the bar. Bar 10 is of non-circular cross-section, preferably square as illustrated herein. Its ends are forged or otherwise finished as screw driver blades 12 and 13 of different shape or size, the width of blade 12 being less than the maximum cross-sectional dimension of the bar and the width of blade 13 in the illustrated case being greater than the maximum width of the bar proper. While I prefer to form both ends of the bar as screw driver blades it will be apparent that one or both ends might be otherwise finished if desired.

The handle 11 which may be of wood, plastic or other suitable material has a square hole or passage 14 extending axially throughout the length of the handle, but if desired one end of the hole may be enlarged as shown at 15 in Fig. 5 in order to accommodate a wide blade such as 13. The relative cross-sectional dimen-

2

sions of the bar 10 and of the hole 14 are such that the bar may be slid lengthwise freely in the handle but such that there will be substantially no looseness or lost motion when torque is applied to the handle.

Spaced from the extremities of bar 10 a distance slightly less than half the length of handle 11, notches 16 are cut out of opposed corners of the bar. These notches are engaged by a releasable latch or lock that is mounted in the handle midway between its ends. This locking means should be held normally in locking position, as by spring means, and when in locking position it should not project substantially beyond the principal contours of the handle. In other words it should not mar the smoothness of the handle.

I have found that the illustrated form of latch is quite satisfactory for the purpose. This latch embodies a metal plate 17 which is disposed in a plane at right angles to the axis of bar 10 and is slidable transversely of the handle. At one end it has a cylindrical post 18 which is either integral with the plate or welded thereto. For the mounting of this plate a hole 19 is bored transversely into the handle nearly all the way across it. From the opposite side a smaller hole 20 is bored to meet hole 19. At the junction of these holes a shoulder 21 is formed. Narrow grooves 22 are machined to extend from hole 19 outwardly at diametrically opposite points. A coil spring 23 is inserted into the hole 19. Then plate 17 is slid into position with its edges in the grooves 22 and its post 18 extending outwardly through the hole 20. The open end of hole 19 is counterbored slightly, and after the plate is inserted a metal plug 24 is forced into the counterbore to permanently close this end of the hole 19 and grooves 22. The side of the handle opposite plug 24 may have a flat 25 machined therein with rounded or beveled edges 26. A button 27 which in normal position is adapted to lie substantially flush with the body of the handle has a cylindrical hub extension which has a press fit upon post 18. Preferably a fiber bushing 28 is interposed between the post and the hub of the button in order to increase the friction between the two parts and make the connection more secure, as well as to insulate the button from the bar 10.

When the handle and the bar 10 are to be moved relatively to each other, the operator must grasp the button 27 and pull it outwardly. To facilitate this manipulation I form two concavities 29 in the handle into which a thumb

and finger of the operator may project. Plate 17 has a slot cut therein which has a narrow portion defining side walls 30 that are spaced apart a distance somewhat greater than the distance across the bar between the two notches 16. This narrow portion of the slot is connected by means of diagonal walls 31 with a larger portion 32 which may be substantially semicircular and at its widest portion is adapted to clear the long cross-sectional dimension of the bar 10, as illustrated in Fig. 4.

When the operator wishes to change the handle 11 from a position at one end of bar 10 to a position at the opposite end thereof he grasps the button 27 between a thumb and finger of one hand and pulls it outwardly against the action of spring 23 until it takes the position of Fig. 4, when the bar may be moved in the handle to disengage the notches 16 at that end of the bar. The operator may then release his hold upon the button 27 and slide the handle along the bar, or the bar in the handle, until the plate 17 encounters the other pair of notches 16, whereupon the spring 23 forces the plate 17 away from the shoulder 21 and into the notches, thereby locking the handle to the bar. The bar may be entirely removed from the handle and a different one put in place therein, but it will be apparent that the bar illustrated in the drawing must be removed by drawing it to the right as viewed in the drawing since the blade 13 is too wide to enter the square hole 14.

Having thus described my invention, I claim:

1. In a tool of the character described, a handle having an endwise passage therethrough of non-circular cross-section, a tool bar of similar cross-section slidable within said passage, each

end of said bar having a pair of opposed notches therein spaced from the extremity of the bar a distance less than half the length of the handle, a latch plate normal to said bar mounted in the middle of the handle for movement transversely thereof, said plate having a slot therein with a wide portion adapted to clear the bar and a narrow portion adapted to enter the opposed notches for preventing longitudinal movement of the bar, a button attached to said plate, said handle having a recess therein adapted to receive said button and a pair of concavities merging with said recess into which an operator's thumb and finger may be projected for engagement with the button, and spring means tending to hold said plate with the narrow portion of the slot in engagement with said notches and to hold said button in said recess.

2. A tool of the character described as defined in claim 1, wherein said passage and said bar are square in cross-section, and wherein said notches are formed in the diagonally opposed corners of the square bar.

ARTHUR F. ALEXANDER.
